CLAIM

The ornamental design for a nasal spray device, as shown and described.

DESCRIPTION

1. Nasal spray device

1.1: Left side view, the Right-side view being a mirror image

1.2 : Bottom

1.3 : Top

1.4 : Top perspective

1.5 : Bottom perspective

1.6: Front side view, the Back-side view being a mirror image

The design relates to a nasal spray device as shown in the reproductions.
